UNITED STATES PATENT OFFICE

ROBERT A. CROOKS, OF CHICAGO, ILLINOIS

POWER DRIVE SELECTIVE MECHANISM

Application filed July 25, 1928. Serial No. 295,189.

This invention relates to improvements in power drive selective mechanism which is adapted for use in connection with power driven typewriters, adding machines, billing machines and other apparatus.

The principal object of the invention is to provide a simple, positive acting mechanism which can be manufactured at low cost and having a few parts, most of which can be stamped from sheet metal.

Another object of the invention is to provide a mechanism which can be compactly assembled in a sound proofed casing, thus eliminating in large measure the noise incident to operation.

Other objects relate to various features of construction and arrangement of parts which will become apparent from a consideration of the following specification and accompanying drawings, wherein:

Figure 1 is a vertical sectional view through a casing, one unit of the mechanism being shown in side elevation.

Figure 2 is a side elevation showing the mechanism in the forward position corresponding to the first step in the cycle of movement.

Figure 3 is a fragmentary side elevation showing the mechanism in a retracted position.

Figure 4 is a broken end view of two similar units.

Figure 5 is a broken longitudinal sectional view of a key lever controlling mechanism.

Figure 6 is a broken perspective view thereof.

In the drawings the mechanism is shown for the purpose of illustration in connection with certain portions of a typewriter, all parts of which not necessary to a clear understanding of the present invention being omitted for the sake of simplicity.

For each key of the machine, such as a typewriter, with which the present invention is employed, an operating unit will be employed, the units being arranged on one or more pairs of rods 10, 11 which may be suitably supported in parallel relation by the frame of the machine.

A unit comprises essentially a key lever 12

provided with a conventional key 13, a carrier 14, and the carrier latch member 15. The key lever is pivotally mounted on the rod 10 and has an arcuate slot 16 which permits of limited movement with reference to the rod 11 which passes through said slot. The lever has a catch 17 which may be integrally formed therewith, and also a small flange or stud 18 which projects laterally from the lever. Another stud 19 is provided at the rear of the lever 12 to be referred to hereinafter.

The carrier or slide 14 is provided with a longitudinal slot 20 by means of which it is slidably mounted on the bars 10 and 11 on the remote side of lever 12. To the rear, or left hand end of the carrier as viewed in Figures 1 and 2, is eccentrically mounted at 21 a cam disk or wheel 22, the periphery of which preferably is milled or serrated to prevent slippage when it is moved into engagement with the power driven cylinder 23 which may be provided with an outer rubber sheath 24. The cylinder 23 is driven by a motor or other power source (not shown) in the direction of the arrow, or counterclock-wise. The cylinder is of a length to serve all the units mounted on the rods 10, 11.

The forward end of the carrier 14 has a horizontal stop flange 25 which in the position shown in Figure 1 is in engagement with the catch 17 of an adjacent lever 12. A coil spring 26 engages with the forward end of the carrier 14, such as with the flange 27 conveniently formed for this purpose. The opposite end of the spring 26 may engage with the hook 28 formed by bending the rear end of the spring 29 partly around the rod 10. The spring 29 passes over the rod 11 and its forward end is bent laterally to engage the lower edge of the key lever 12. The spring 29 thus tends to hold the lever 12 in the position shown in Figure 1, in which position the catch 17 engages the stop 25 and prevents the carrier 14 from moving to the left under the action of the spring 26.

The latch 15 is oscillatably mounted on the rod 11 on the near side of lever 12 as viewed in Figure 1 and is provided with a latch setting arm 15a and stop arm 15b as shown. Arm 100

- 15a has a lateral extension 30 which passes under lever 12 and into position for engagement with the curved or cam shoulder 14a of the carrier 14 when the latter is moved to fully retracted position as hereinafter described. The arm 15b has an edge 31 which acts as a stop for engagement by the flange 25 when the mechanism is in the position shown in Figure 3.
- 10 A cycle of operation of the apparatus will now be described. When the key 13 is depressed by the operator, the lever 12 is moved about the rod 10, (the arcuate slot 16 permitting such movement) thus causing the catch 17 to be moved from the path of the stop 25, whereupon the spring 26 moves the carrier 14 and cam disk 22 to the left to the position shown in Figure 2. In this position the stop pin 22a is clear of the lug 19 and the disk is free to rotate on the eccentric axis 21, due to the tractive force of the power driven rotating cylinder 23. The disk 22 thus rotates clockwise and forces the carrier to the right against the action of the spring 26. The throw of the disk is sufficient to move the carrier to the right beyond the position shown in Figure 1 and thus actuates the type bar 33 or other operating member or mechanism by means of the link 34, the bar being pivoted at 35 to any suitable part of the operating machine and being retracted to normal position by the conventional spring 36. The link 34 slides in a slot 37 on the carrier 14 on the forward stroke of the latter and thus does not move the member 33 from the position shown in Figure 1 except when the disk 22 is in the position of maximum throw. In this position of maximum throw of the cam disk 22, the flange 25 is approximately in the position shown by dotted lines in Figure 3 which permits the stop arm 15b to move to the position shown in Figure 3. This clockwise movement of the latch 15 is effected by the curved cam position 14a of carrier 14 engaging the extension 30 of the arm 15a as the carrier 14 makes the return movement under action of the cam disk 22. The engagement of the flange 25 by the arm 15b prevents an unintentional repetition of the stroke of the carrier 14 and of the type bar 33 which otherwise would occur should the key lever 12 be held in depressed position during this portion of the cycle of operation. It thus will be seen that this automatic stopping of the carrier 14 is positive since the latch member 15 is actuated directly by the carrier. Regardless of the speed of the return movement of the carrier, it will be prevented from repeating by the latch. Upon removal of the operator's finger from the key 13, the spring 29 moves it upwardly or counterclockwise around the rod 10 to the position shown in Figure 1. During this upward movement the lug 18 engages the lower edge of arm 15b and moves it from the position shown in Figure 3 to the position il-

lustrated in Figure 1, the latch 17 moving up simultaneously to engage the flange 25, in which position the parts are ready for a similar cycle of operations upon the depression of the key lever 12. Upon the engagement of the stop flange 25 by the edge 31 of arm 15b, the cam disk 22 clears the roller or cylinder 23 and is carried by its momentum until it is stopped in normal position by the stud 22a coming in contact with the lug 19 of the adjacent unit.

The units are arranged in parallel relation on the bars 10 and 11 and may be held in spaced relation by any suitable means such as the pins 38, 38.

The several units may be enclosed in a casing 40 having a lining 41 of felt or other sound deadening material to quiet the operation of the mechanism, suitable slots being provided for the key levers 12 and the links 34.

To prevent the depression of more than one key lever at a time, I have provided a controlling mechanism comprising a casing 42 which is suitably mounted in any operative position with reference to the levers 12, as on the front of the casing 40. The casing 42 may be rectangular in cross section and provided with longitudinal inwardly depressed ribs 43 which form supports or bearings for the balls 44 longitudinally movably within the casing. Slots 45 are provided in the casing, one for each key lever 12. The balls are of such size, with reference to the length of the casing and thickness of the levers, that when one lever has been depressed into its respective slot, the balls at each side of said lever are in contact, that is, there is sufficient spare space in the casing to accommodate one lever only. Hence when one lever is depressed, wedging the balls laterally of the casing, the remaining slots are obstructed, thus preventing the simultaneous operation of two or more levers. The ribs 43 permit the balls to move freely within the casing.

In Figure 3 the arm 15a of the latch 15 is shown provided with a roller 15c which reduces friction upon contact with the cam surface 14a of the carrier or slide member 14.

The mechanism described can be made largely of sheet metal and as the parts are relatively simple and few in number the initial cost of the dies for manufacturing will be much less than has been the case with certain prior apparatus.

The invention has been shown and described with particular reference to a type-writing machine but it will be apparent that it is adapted for use with a variety of other mechanisms and may be operated by other than manual means, such as by magnetic means. Although I have disclosed one specific form of my improvements for the purpose of illustration it will be seen that various changes may be made therein without de-

parting from the spirit of the invention, and I do not wish to be restricted specifically thereto except where so limited by the appended claims.

What I claim is:

movement of said slide, an oscillatable latch having a stop portion and a setting portion, said setting portion being actuatable by said slide for moving said stop portion into the path of said slide stop for preventing a second forward stroke of said slide while said catch is in slide releasing position, a spring for moving said lever to normal position when released by the operator, and a lug on said lever for moving said latch out of operative position simultaneously with the return movement of said catch into engagement with said slide stop, said disk having a pin for engaging a relatively stationary member on an adjacent lever for limiting the rotation of said disk after the retraction of said slide.

7. Mechanism of the class described comprising a pair of parallel supporting rods, a depressible operating lever pivoted on one of said rods, a latch pivoted on the other rod, a slide having an elongated slot through which said rods pass and on which said slide is reciprocable, said lever having a catch for engaging said slide for holding the latter in retracted position when said lever is un-depressed, means for moving said slide forwardly upon the depression of said lever to release said catch, means for retracting said slide, an operating member actuatable by said slide upon the retraction thereof, said latch having means engaged by said slide upon the return movement thereof for moving said latch into position to prevent a second forward movement of said slide while said lever remains depressed, and a member on said lever for moving said latch to inoperative position simultaneously with the return movement of said catch to slide engaging position.

40 In witness whereof I have subscribed my name.

ROBERT A. CROOKS.
